(57) **CLAIM**

The ornamental design for a launching apparatus for spinning top toy, as shown and described.

DESCRIPTION

FIG. 1 is a front top and right perspective view showing out new design for a launching apparatus for spinning top; FIG. 2 is a left side view thereof; FIG. 3 is a rear view thereof; FIG. 4 is a right side view thereof; FIG. 5 is a top view thereof; FIG. 6 is a bottom view thereof; FIG. 7 is a perspective view thereof; FIG. 8 is a front top and right perspective view; showing the design in a disassembled state; FIG. 9 is a rear, bottom and left perspective view; showing the design in a disassembled state; FIG. 10 is a front top and left perspective view showing the design with a spinning top toy attached thereto; FIG. 11 is an inverted right, bottom and front perspective view showing the handle portion of the design in an alternate configuration and supporting a smartphone; and, FIG. 12 is a perspective view as in FIG. 11, but shown without the smartphone.

The broken lines showing the spinning top toy in FIG. 10 and the smartphone in FIG. 11 are for illustrative purposes only and form no part of the claimed design.

1 Claim, 12 Drawing Sheets
